US00D568532S

(12) **United States Design Patent** (10) Patent No.: **US D568,532 S**
Compton (45) Date of Patent: ** May 6, 2008

(54) **LIGHTING FIXTURE SUPPORT ARM**

D63,602 S 12/1923 Ainsworth
D72,912 S 6/1927 Peinlich
D73,934 S 11/1927 Lindsay

(75) Inventor: **Wayne W. Compton**, Chino Hills, CA
(US)

(Continued)

(73) Assignee: **Hubbell Incorporated**, Orange, CT
(US)

Primary Examiner—Freda S. Nunn
Assistant Examiner—Kevin K Rudzinski

(**) Term: **14 Years**

(74) Attorney, Agent, or Firm—Jenae C. Avallone; Mark S. Bicks; Alfred N. Goodman

(21) Appl. No.: **29/287,975**

(57) **CLAIM**

(22) Filed: **Oct. 5, 2007**

The ornamental design for a lighting fixture support arm, as shown and described.

(62) Division of application No. 29/222,800, filed on Feb. 4, 2005, now Pat. No. Des. 556,945.

DESCRIPTION

(51) **LOC (8) Cl.** 26-99
(52) **U.S. Cl.** D26/155

(58) **Field of Classification Search** D26/155,
D26/145, 71, 60, 68, 113, 118, 24, 61, 62,
D26/63, 64, 67, 72, 93, 138, 140, 141, 142,
D26/150, 151, 152, 153, 154; 362/147, 151,
362/153, 224, 257, 277, 280, 285, 287, 368,
362/370, 441, 432; 248/205.1; D6/332,

FIG. 1 is a top plan view of a lighting fixture support arm in accordance with the present invention;

FIG. 2 is a left side view of the lighting fixture support arm illustrated in FIG. 1;

FIG. 3 is a front view of the lighting fixture support arm illustrated in FIGS. 1 and 2;

FIG. 4 is a right side view of the lighting fixture support arm illustrated in FIGS. 1-3;

FIG. 5 is a bottom view of the lighting fixture support arm illustrated in FIGS. 1-4; and,

FIG. 6 is a perspective view of the lighting fixture support arm illustrated in FIGS. 1-5 showing the arm supporting a light fixture mounted to a pole.

The broken lines are shown for illustrative purposes only and form no part of the claimed design.
